UNITED STATES PATENT OFFICE

WILLIAM H. WHALEN, OF BEVERLY HILLS, CALIFORNIA, ASSIGNOR TO CONTINUOUS
RAIL CROSSING CORPORATION, OF RENO, NEVADA, A CORPORATION OF NEVADA

INDICATOR

Application filed December 11, 1929. Serial No. 413,251.

My invention relates to crossings at the intersections of two or more railroad tracks and is particularly related to means for indicating the position of turntables in the 5 crossings.

In railroad crossings it has become the practice to dispose a rotatable grooved turntable in a suitable base at each intersection of a pair of rails so that four turntables 10 are used at each crossing.

An object of my invention is to provide means for indicating the position of the turntables in the crossing.

Another object of my invention is to provide 15 positive means for indicating the position of each turntable in the crossing independent of the other three turntables.

A further object of my invention is to provide 20 means for locking the turntables in their extreme position.

A still further object of my invention is to provide means for locking the turntables in either extreme position in case of emergency or for any other reason.

25 Other objects together with some of the advantageous features of my invention will be set forth in the following discussion where I shall outline the preferred embodiment of my invention. In the drawings I have shown 30 one embodiment of my invention but it is to be understood that I do not limit myself to such form since the invention, as set forth in the appended claims, may be embodied in a plurality of forms.

35 Figure 1 is a plan view of a rail intersection showing the preferred embodiment of my invention, parts being broken away to disclose the construction.

40 Figure 2 is a cross section through the rail intersection, the plane of section being indicated by the line 2-2 of Figure 1.

45 In its preferred aspect, my invention comprises a rail intersection formed with a casing in which is rotatably mounted a turntable having a groove in its upper face adapted to register, in either of two extreme positions, with either of the intersecting rails, together with an emergency lock for locking the turntable in its extreme positions, locking means 50 for locking the turntable in its extreme posi-

tions, turning means for revolving the turntable between its extreme positions, and an indicator for disclosing the position of the turntable.

At each pair of intersecting rails 2 and 3 55 in a crossing, I preferably provide a casing 4 which is conveniently formed integral with the intersecting rails or which may be formed separately therefrom. Each of the casings is of cylindrical interior contour to receive 60 a generally cylindrical turntable 6 having a diametrical groove 7 in its upper surface.

The turntable is adapted to be rotated within the casing, the groove 7 being of such form and dimensions as to register or be in alignment with either of the rails 2 or 3 when the turntable is placed in its extreme positions. The turntable is preferably provided with a centrally depending extension 8 journaled within the casing 4 and having a non- 70 circular seat 9 adjacent its lower end.

Means are provided for suitably rotating the turntable. The turning means include a lever 10 having a non-circular aperture therein adapted to engage the seat 9. The lever 10 75 is also secured to a shaft 11 and this linkage for revolving the turntable may be controlled from any suitable point such as a signal tower 25.

In order to secure the turntable 6 in either 80 extreme position in emergencies or whenever it is deemed advisable, I provide a suitable locking bolt 12 in threaded engagement with the casing. This bolt, upon rotation, can be projected into either of two radial recesses 85 13 and 14 in the turntable, thus precluding any rotation thereof. I also provide remotely controlled means for locking the turntable in either extreme position. This means includes a locking pin 16, having a head 17, pivoted to lever 18 engaged by an arm 19 which is controlled from a suitable point such as the signal tower 24. This pin 16, upon operation of the linkage just described, can be projected into either of two radial recesses 90 21 and 22 in the turntable, thus precluding any rotation thereof.

95 Means for positively indicating the position of the turntable are provided and preferably include a pair of superimposed pins 23 100

and 24 which are adapted to be actuated by complementary cam surfaces 26 and 27 formed upon the periphery of the turntable 6. The pins are pivotally connected to the opposite ends of a rocker 28 which is secured to a shaft 29 journaled in the casing 4. The shaft conveniently is provided with an extension 31 on which one end of a rod 32 is pivotally connected. The other end of the rod 32 is in engagement with an indicator such as a semaphore adapted to lie in either position 33 or 34 corresponding to the position of turntable 6.

The semaphore which is adapted to indicate the position of the turntable is operated by the above described linkage in the following manner. As the turntable is rotated to place the groove 7 in alignment with the rail 2, cam surface 26 bears upon pin 23 and, since the pin is pivotally connected to the rocker 28, actuates the rocker and causes the shaft 29 to be rotated which in turn moves the rod 32 to place the semaphore as indicated at 33 in the signal tower. As the turntable is rotated to place the groove 7 in alignment with the rail 3, the cam surface 27 of the turntable 6 bears upon the pin 24 thereby actuating the rocker 28, the shaft 29 and the lever 32 to place the semaphore in the position 34 in the signal tower.

My invention, as just described, affords positive means for indicating the position of the turntable in the crossing and hence that the crossing is or is not in safe condition for the passage of cars.

I claim:

1. A rail crossing comprising intersecting rails, a casing at the intersection of said rails, a turntable in said casing adapted to rotate therein between two extreme positions, said turntable having a groove in its upper surface adapted to be aligned in said extreme positions with either of said rails, means for revolving said turntable, and means adapted to be moved by a cam surface on said turntable for indicating the position of said turntable.

2. A rail crossing comprising intersecting rails, a casing at the intersection of said rails, a turntable in said casing adapted to rotate therein between two extreme positions, said turntable having cam surfaces formed upon its periphery and a groove in its upper surface adapted to be aligned with either of said rails, means for revolving said turntable, means adapted to bear upon said cam surfaces, and means engaging said last named means for indicating the position of said turntable.

3. A rail crossing comprising intersecting rails, a casing at the intersection of said rails, a turntable in said casing adapted to rotate therein between two extreme positions, said turntable having cam surfaces formed upon its periphery and having a groove in its up-

per surface adapted to be aligned in said extreme positions with either of said rails, means for revolving said turntable, indicating means adapted to be moved by said cam surfaces, and means for locking said turntable in either extreme position.

4. A rail crossing comprising intersecting rails, a casing at the intersection of said rails, a turntable in said casing adapted to rotate therein between two extreme positions, said turntable having cam surfaces formed upon its periphery and having a groove in its upper surface adapted to be aligned in said extreme positions with either of said rails, a pair of superimposed pins adapted to bear upon said cam surfaces, means secured to and adapted to be actuated by said pins for indicating the position of said turntable, a locking pin in threaded engagement with said casing for locking said turntable in either extreme position, and means for rotating said turntable.

5. An indicator comprising a pair of intersecting rails, a casing secured to said rails, a turntable in said casing adapted to be rotated therein, said turntable having cam surfaces formed upon its periphery and having a groove in its upper surface adapted to be aligned with either of said rails, a pair of superimposed pins in engagement with said cam surfaces and adapted to be moved, means for rotating said turntable, means in engagement with said pins for indicating the position of said turntable, and means for locking said turntable in either of its extreme positions.

In testimony whereof, I have hereunto set my hand.

WILLIAM H. WHALEN.
